THREAD HOLDER FOR WEFT REPLENISHING LOOMS

Walter H. Wakefield, Worcester, Mass., assignor to
Crompton & Knowles Loom Works, Worcester,
Mass., a corporation of Massachusetts

Application April 21, 1944, Serial No. 532,093

14 Claims. (Cl. 139—247)

This invention relates to improvements in thread holder mechanism for the weft ends of reserve bobbins in weft replenishing looms and it is the general object of the invention to provide driving means which causes the thread holder mechanism to operate continuously and at a rate more or less proportional to the frequency with which replenishing operations occur in the loom.

In weft replenishing looms more particularly of the multicolor type the reserve bobbins are held in stacks or guideways down which they move toward a common transfer position. The bobbins descend in a vertical path but their weft ends extend diagonally to the thread holder, and at each descent of bobbins in a stack some slackness of the weft ends occurs. It is desirable that this slackness be taken up so that the weft ends may be kept out of the path of the lay.

The rate at which the thread holder should tend to take up slackness in the weft ends bears a close relation to the frequency with which slackness occurs in the weft ends due to replenishing operations of the loom. The take-up roll of the loom also has a movement the rate of which is closely related to the frequency of transfer and it is an important object of my present invention to provide driving connections between the take-up roll and the thread holder mechanism.

The relation between the take-up roll and the frequency of transfer will be apparent from a consideration of the sizes of yarns which are used as weft in the loom. If the weft is coarse so that the fabric being woven has only 20 picks per inch, for instance, a comparatively small number of picks only can be wound on the bobbins and the rate of transfer will be high. Under these conditions the take-up roll is adjusted so that it moves with a relatively rapid rate in order to take up the cloth. On the other hand, if the weft is fine and the fabric being woven has for instance 60 picks per inch, more picks of weft can be wound on the bobbins and there will be a lowered rate in the replenishing operations of the loom. Under these latter conditions the take-up roll driving mechanism will be set to drive the roll much more slowly than in the first condition mentioned. It is apparent therefore that the rate at which the take-up roll turns is closely related to the rate at which transfer operations occur in the loom.

It is another object of my present invention to provide a flexible shaft which operatively connects the take-up roll to geared thread holder

members between which the weft ends extend. The flexible shaft preferably extends through and is supported on the bobbin magazine in such position as not to interfere with the transerrer arm or the descent of bobbins in their stacks.

It is another object of my present invention to provide a train of driving connections between the take-up roll and the gears of the thread holder constructed to include change gear devices which, in any given setting, will establish proper relative rates between the take-up roll and the thread gears for the particular fabric being woven.

As the bobbins await transfer they tend to turn on their axes and cause slackness in their weft ends. It is a further object of my invention not only to drive the thread holder mechanism at a rate proportional to the replenishing rate, but also drive it continuously during loom operation to take-up the slackness resulting from rotation of the bobbins.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a front elevation of the weft replenishing end of a loom having my improved thread holder mechanism applied thereto,

Fig. 2 is a plan view looking in the direction of arrow 2, Fig. 1.

Fig. 3 is an enlarged end elevation of the thread holder looking in the direction of arrow 3, Fig. 1, with the guard plate partly removed, and showing the interior of the casing or housing on which the thread gears are mounted,

Fig. 4 is a vertical section on line 4—4 of Fig. 3.

Fig. 5 is an enlarged detail end elevation looking in the direction of arrow 5, Fig. 4.

Fig. 6 is an enlarged vertical section of a portion of Fig. 4 showing the connection between the flexible shaft and the shaft of the driven thread engaging gear;

Fig. 7 is an enlarged plan view of one end of the take-up roll and the parts of my invention adjacent thereto,

Fig. 8 is a side view looking in the direction of arrow 8, Fig. 7, the breast beam being in section,

Fig. 9 is a vertical section on line 9—9, Fig. 7.

Figs. 10 and 11 show a fabric and a bobbin, respectively, with coarse weft,

Figs. 12 and 13 are similar to Figs. 10 and 11 except that the weft is fine,

Fig. 14 is an enlarged fragmentary side elevation looking in the direction of arrow 14, Fig. 1, and

Fig. 15 is an enlarged front elevation of the supporting arm for the flexible shaft projecting from the magazine toward the thread holder.

Referring particularly to Figs. 1 and 2, I have shown the loom frame 10 of a weft replenishing loom and a lay 11 reciprocating backwardly and forwardly during loom operation and supporting a shuttle S which is propelled by picking mechanism designated generally at 12. A bobbin magazine M is held in stationary position over the lay and is provided with several stacks of reserve bobbins B. As shown in Fig. 2, four stacks of these bobbins are employed but my invention is not necessarily limited to their number of stacks in the magazine. Extending from the bobbins are weft ends W which lead downwardly and outwardly from the magazine to a thread holder mechanism designated generally at H. This thread holder includes in its construction front and back geared members 15 and 16, respectively, mounted on a casing or support 17 in such position that the weft ends may be drawn downwardly between said geared members. An arm 18 secured in any approved manner to the magazine extends diagonally downwardly behind the latter to hold the support 17 as at 19.

A take-up roll 20 is mounted in the forward part of the loom and is driven by mechanism not shown but well understood and located at that end of the loom opposite the end shown in Fig. 1. In Figs. 1, 2, 7 and 8 there is shown one of the bearings or supports 21 for the take-up roll secured to the breast beam 22 of the loom and provided with a cap 23 which forms part of the bearing which receives gudgeon 24 projecting from the roll 20.

During loom operation the roll 20 is moved in the direction of arrow a, Fig. 8, to take up the fabric F as the latter is formed at the fell of the cloth. As weaving continues the running weft will become depleted from time to time and will be replenished by bobbins drawn from the magazine. At each replenishing operation one of the bobbins will descend to a position under transerrer arm 27 for insertion into shuttle S. At this time a certain amount of slackness in the bobbins of the stack from which the transferred bobbin is drawn will result due to the fact that the bobbins descend vertically but their weft ends extend diagonally toward the thread holder H. This slackness should be taken up in order to keep the weft ends taut as shown in Fig. 1 and above the path of the lay 11, and it is the general purpose of my present invention to provide driving connections between the take-up roll 20 and the geared members 15 and 16.

The matter thus far described is of common construction and may be made according to common practice, the geared members 15 and 16 if desired being similar to those shown for instance in patent to Payne No. 1,842,731.

In carrying my present invention into effect I employ a train of driving connections between the take-up roll and one of the thread gears of the thread holder. This train includes a flexible shaft 30 having a sheath 31 and a core 32 rotatable within the sheath. As shown more particularly in Figs. 7 and 8 I provide a gear 35 located alongside the bearing 21 and held tightly to the gudgeon 24 by a screw 36 tapped into

said gudgeon. In this manner the gear 35 is caused to turn with the take-up roll in the direction of arrow a, Fig. 8. A carrier arm 37 has the lower end thereof held to the bearing support 21 by a pivot screw 38 tapped into bearing 21, while the upper end of the carrier is formed with a slot 39 and has extending therethrough a screw 40 also tapped into the take-up bearing member. The screw 38 serves as a pivot when both screws are loosened so that the carrier can move to different angular positions at varying distances from the gear 35, but when both screws are tightened the carrier is held in fixed position relatively to the loom frame.

The carrier is provided with a bearing 41 in which rotates a stub shaft 42, the right end of which, see Fig. 9, projects beyond the right end of bearing 41 and is secured to the core 32 of the flexible shaft in any approved manner, as by welding or brazing. A cotter pin 43 limits movement of the stub shaft to the left with respect to bearing 41 as viewed in Fig. 9, and the left end of shaft 42 has secured thereto a pinion 45 which is held in mesh with gear 35 as shown in Fig. 8. As the take-up rotates the pinion and therefore core 32 will be driven in a clockwise direction as viewed in Fig. 8.

The flexible shaft 30 extends to the right from the stub shaft 42 and may be secured as at 46 to a fixed part of the loom, such as the breast beam, and then extends through the magazine M. The transerrer arm 27 which comes into action at the time of a replenishing operation extends through an opening 48, see Fig. 14, formed in the inner plate or end frame 49 of the magazine M. The flexible shaft passes through this opening 48 and is held out of interfering position with respect to the transerrer arm by means of a supporting wire 50 which is supported by screws 51 tapped into the end frame 49. The shaft 30 extends as shown in Fig. 2 between the front and back pairs of bobbin stacks and may then extend along a support arm 52, see Figs. 1, 2 and 15. As shown in Fig. 15 the arm 52 is held to the outer plate or end frame 53 of the magazine by means of a screw 54 and has upwardly extending fingers 52' which guide the flexible shaft 30 as the latter extends to the thread holder for attachment to geared member 15.

The casing or support 17 of the thread holder has a vertical outside wall 55 and front, back, top and bottom walls 56, and a guard plate 57 is secured as at 58 to the front and back walls. As shown more particularly in Fig. 4, the front geared member 15 is clamped by a nut 60 on a shaft 61 against a flange 62 integral with the shaft. The shaft is rotatable in a bearing 63 formed as part of the outside wall 55 and projects to the left beyond said bearing as suggested in Figs. 4 and 6. The shaft 61 has the end thereof split as at 65 and is provided with a tapered thread 66 for a similarly tapped nut 67. Extending through the slotted part of the shaft 61 is a hole 68 which receives the core 32 of the flexible shaft, see Fig. 6. When the nut 67 is set tightly on shaft 61 it compresses the split end thereof to clamp the left split end of the shaft firmly against the core 32 for the purpose of establishing a driving connection between these two parts.

In order to provide support for the sheath 31 of the flexible shaft I provide the construction shown in Figs. 4 and 5. A fitting 70 has a base 71 secured at 72 to the removable plate 57 and

is provided with a bearing 13 formed in part by two upwardly extending arms 14 through which extends a bolt 75 having a nut 76 on one end thereof. When the bolt is loose the fitting 70 and the plate 57 can be slid along the shaft 30, but when bolt 75 is tightened and the bearing arms 14 have been clamped against the shield 32 the latter is supported on plate 57 in such position that the flexible shaft can lead directly to the stub shaft 61.

During loom operation the take-up roll 20 rotates and causes the pinion 45 to turn the core 32 and therefore geared member 15 in a clockwise direction as viewed from the thread holder end of the loom, or in a counter-clockwise direction as viewed in Fig. 3. The geared members mesh with each other so that continuous turning of member 15 causes turning of member 16 and the weft ends which extend between these members are therefore drawn downwardly between the latter and subjected to a tension which takes up any slackness due to rotation of the bobbins on their axes as they await transfer. This rotation of the gears 15 and 16 continues uniformly during loom operation, but at a rate slow enough so that no undesired abrasion of the weft ends results. When a replenishing operation of the loom occurs the selected bobbin will be inserted into the shuttle 8 and its weft end will be held by the thread holder as the shuttle is picked to the opposite end of the loom. All the bobbins located above the selected bobbin will drop in their stack and a slight amount of slackness will occur in the corresponding weft ends. This slackness, however, will be taken up by the turning gears 15 and 16 and in a short period of time the weft ends will again be taut. During the short interval of slackness, however, the threads will still be located above the path of the lay so that the latter will not interfere with or break the weft ends.

In Figs. 10 and 12 I show two types of fabric F' and F2, respectively, which can be woven in the loom, Fig. 10 showing horizontal lines representing coarse weft while Fig. 12 shows that fabric F2 is woven with finer weft. Fig. 11 shows bobbin BC having coarse weft used in fabric F', while Fig. 13 shows a bobbin BF having fine weft used in fabric F2. Fabric F' may have 20 picks per inch, for instance, while fabric F2 may have 60 weft threads per inch. When the fabric shown in Fig. 10 is being woven the take-up roll will be driven at a relatively fast rate of speed and it will be obvious because of the coarseness of the weft that the loom will have frequent replenishing operations involving bobbins similar to bobbin BC, but when the fabric shown in Fig. 12 is being woven the driving mechanism for the take-up roll will be set so that the latter will turn at a slow rate, and there will be fewer replenishing operations of the loom involving bobbins such as BF. It is thus apparent that the rate at which the take-up roll 20 turns in the loom is closely related to the number of replenishing operations of the loom, and it will further be apparent that the gears 15 and 16 turn at a faster rate when the replenishing operations are frequent than is the case when said operations are less frequent. The thread holder is thus driven continuously during loom operation but at a rate closely proportioned to the rate at which slackness occurs in the weft ends due to replenishing operations.

It may not always be desirable to operate the

thread holder by the gear 35, and it is to provide a change gear mechanism between the take-up roll and thread holder that I have pivoted the carrier 37. If it should be necessary to drive the thread holder at a faster rate, for instance, carrier 37 can be swung to the dotted line position shown in Fig. 8 and a second gear 35a used to replace gear 35. The carrier arm will be fastened in position with the pinion 45 in mesh with the new gear, after which the mechanism will operate as already described except that the thread gears 15 and 16 will turn at a faster rate than would be the case if the gear 35 were used.

From the foregoing it will be seen that I have provided thread holder mechanism operating continuously during operation of a weft replenishing loom and so constructed that it operates at a rate more or less proportional to the rate at which replenishing operations occur in the loom. It will further be seen that this result is accomplished by a connection between the take-up roll and the geared members 15 and 16. The take-up roll moves at substantially the same rate as does the fabric and the roll may be considered as a means the rate of turning of which is determined by the rate at which the cloth moves through the loom. It will also be seen that change gear mechanism is provided and that gear 35 can if desired be replaced by another gear of different size so that the ratio of drive between the take-up roll and pinion may be varied. It will also be noted that the flexible shaft extends through the magazine and is supported thereby in such position as not to interfere with the transfer arm or descent of the reserve bobbins in their respective stacks. Furthermore, the slackness of the weft ends incident to rolling of the bobbins in the magazine is taken up due to the continuous operation of gears 15 and 16.

Having thus described my invention it will be seen that changes and modifications may be made therein by those skilled in the art without departing from the spirit and scope of the invention and I do not wish to be limited to the details herein disclosed, but what I claim is:

1. In thread holder mechanism for a weft replenishing loom having reserve bobbins from which weft ends extend, meshing geared members between which said weft ends extend, a take-up roll which turns during loom operation, and driving connections between said take-up roll and one of said geared members effective to turn the latter to tension said weft ends as the take-up roll turns.

2. In thread holder mechanism for a weft replenishing loom having reserve bobbins from which weft ends extend, meshing geared members between which said weft ends extend, a take-up roll which turns during loom operation, and driving connections between said take-up roll and one of said geared members operative as said take-up roll turns to cause said geared members to turn in a direction to draw said weft ends away from said bobbins.

3. In thread holder mechanism for a weft replenishing loom having reserve bobbins from which weft ends extend, meshing geared members between which said weft ends extend, a take-up roll which turns during loom operation, a flexible shaft having one end operatively connected to one of said geared members and having the other end operatively connected to said take-up roll and effective due to rotation of said take-up roll to

cause said geared member to turn and tension said weft ends.

4. In thread holder mechanism for a weft replenishing loom having a magazine supplied with reserve bobbins from which weft ends extend, meshing geared members located on one side of said magazine and between which the weft ends extend, a take-up roll turning during loom operation and located on the other side of said magazine, and a flexible shaft extending through and supported on said magazine and operatively connected at one end thereof to one of said geared members and operatively connected at the other end thereof to said take-up roll, said flexible shaft operative when the take-up roll is turning to cause said geared members to turn and tension said weft ends.

5. In thread holder mechanism for a weft replenishing loom having weft ends extending therefrom, meshing geared members between which said weft ends extend, a take-up roll which turns during loom operation, driving means connected to one of said geared members, and change gear mechanism operatively connecting the take-up roll and said driving means and causing the latter to turn the geared members to tension said weft ends when the take-up roll turns.

6. In thread holder mechanism for a weft replenishing loom having reserve bobbins from which weft ends extend, meshing geared members between which said weft ends extend, a take-up roll which turns during loom operation, a gear secured to and turning with said take-up roll, a pinion meshing with said gear and rotatably mounted on the loom, and driving connections between said pinion and one of said geared members operative during loom operation to turn said geared members by a force derived from the take-up roll and in a direction to tension said weft ends.

7. In thread holder mechanism for a weft replenishing loom having reserve bobbins from which weft ends extend, meshing geared members between which said weft ends extend, a take-up roll which turns during loom operation, a gear secured to and turning with said take-up roll, a pinion for said gear, a carrier on which said pinion is rotatably mounted, a pivot on the loom for said carrier, means cooperating with said pivot to hold the carrier in fixed position on the loom with the pinion meshing with the gear, and driving connection between the pinion and one of said geared members operative to turn the latter to tension said weft ends as the take-up roll turns.

8. In thread holder mechanism for a weft replenishing loom having reserve bobbins from which weft ends extend, meshing geared members between which said weft ends extend, the fabric being woven in the loom moving therethrough at a given rate, means engaging the fabric and moving at substantially said given rate, and a train of driving connections between said means and one of said geared members causing the latter to move to tension said weft ends as said means moves.

9. In a weft replenishing loom having a magazine provided with two pairs of vertically arranged stacks of reserve bobbins from which weft ends extend, a take-up roll on one side of said magazine, thread holder mechanism for said weft ends on the other side of said magazine, and a train of mechanism operatively connecting said take-up roll and thread holder mechanism

and including a flexible shaft passing through said magazine between said pairs of stacks of reserve bobbins.

10. In a weft replenishing loom provided with a magazine having inner and outer end frames between which are arranged reserve bobbins from which weft ends extend, a take-up roll on one side of said magazine, thread holder mechanism for said weft ends on the other side of said magazine, and a train of mechanism operatively connecting said take-up roll and thread holder mechanism and including a flexible shaft supported on said end frames.

11. In a weft replenishing loom provided with a magazine having an end frame provided with an opening for a transerrer arm and having reserve bobbins from which weft ends extend, a take-up roll on one side of said magazine, thread holder mechanism on the other side of said magazine, and a train of mechanism operatively connecting said take-up roll and thread holder mechanism and including a flexible shaft passing through said opening and supported on said end frame out of engagement with said transerrer arm.

12. In a weft replenishing loom having a magazine for reserve bobbins from which weft ends extend, the loom having a lay reciprocating below said magazine, thread holder mechanism for said weft ends, a flexible shaft extending from the magazine above said lay and operatively connected to said thread holder mechanism, and means on said magazine above the lay supporting said flexible shaft above and out of engagement with the lay.

13. In a weft replenishing loom having a stack of reserve bobbins from which weft ends extend, slackness in said weft ends being due to two factors one of which results from rotation of the bobbins on their axes during loom operation and the other factor resulting from descent of the bobbins in said stack incident to weft replenishing operations of the loom, thread holder mechanism which when operated takes up said slackness in the weft ends, and means operating said thread holder mechanism continuously during loom operation to take up the slackness in the weft ends due to the first of said factors and said means also operating said thread holder mechanism to take up slackness in said weft ends due to said other factor at a rate which is faster when the fabric being woven has coarse weft requiring frequent replenishing operations than when the fabric being woven has fine weft requiring less frequent replenishing operations.

14. In thread holder mechanism for a weft replenishing loom from which weft ends extend and having a take-up roll the rate of turning of which varies with the frequency with which replenishing operations occur in the loom, said take-up roll turning at one rate when said replenishing operations are frequent and turning at a slower rate when said replenishing operations are less frequent, meshing geared members between which the weft ends extend, said members being rotatable to tension the weft ends, and driving connections between said take-up roll and one of said geared members operative to turn the latter to tension said weft ends as the take-up roll turns, said driving connections causing said geared members to turn faster when the take-up roll is turning at said one rate than when said take-up roll is turning at said slower rate.
